D. C. DAVIS.
KEEP ALIVE ANODE.
APPLICATION FILED MAY 11, 1914.

1,222,537.

Patented Apr. 10, 1917.

UNITED STATES PATENT OFFICE.

DAVID C. DAVIS, OF SWISSVALE, PENNSYLVANIA, ASSIGNEE TO WESTINGHOUSE ELECTRIC AND MANUFACTURING COMPANY, A CORPORATION OF PENNSYLVANIA.

KEEP-ALIVE ANODE.

1,222,537.

Specification of Letters Patent. Patented Apr. 10, 1917.

Application filed May 11, 1914. Serial No. 837,725.

To all whom it may concern:

Be it known that I, DAVID C. DAVIS, a citizen of the United States, and a resident of Swissvale, in the county of Allegheny 5 and State of Pennsylvania, have invented a new and useful Improvement in Keep-Alive Anodes, of which the following is a specification.

My invention relates to vapor electric apparatus and more specifically to the solid electrodes employed therein, and it has for its object to provide an electrode which will operate to give a stable arc for a long period of time without artificial cooling.

15 In the construction of vapor electric apparatus, especially mercury-arc rectifiers of the heavy-current type, it has been customary to construct the main anodes of hollow steel and to provide them with fluid cooling 20 means in order to prevent excessive heating. The small anode employed for the maintaining or keep-alive arc has not been cooled, however, but has been constructed of a small rod of refractory material such, for 25 example, as tungsten. This rod slowly melts or volatilizes until, at last, the path for the keep-alive arc is so long that it is necessary to supply an excessive amount of power thereto in order to maintain the rectifier in operation. By my invention, simple and economical means are provided for feeding forward the tungsten rod in accordance with the wasting away thereof, and the 30 keep-alive arc is maintained at the most 35 favorable length and power consumption.

In the accompanying drawing, Figure 1 is a view, partially in section and partially in elevation of a rectifier embodying my invention; Fig. 2 is a sectional view of the electrode employed in Fig. 1; Fig. 3 is a side view, partially in section and partially in elevation, of the electrode employed in Fig. 40 1; Fig. 4 is a view, in section, of a modified form of electrode; Fig. 5 is a side view, in 45 elevation, of another form of electrode; Fig. 6 is a side view, in section, of the electrode rest shown in Fig. 1, and Fig. 7 is a view, in plan of the rest shown in Fig. 6.

An evacuated container 1 of any suitable 50 material, such, for example, as steel, is provided with a main anode 2 and a liquid cathode 3. The anode 2 is preferably water cooled by means of tubes 23 and 24. Current is supplied to the anode by a conductor 4 and taken from the cathode by means of the

container wall and a conductor 5. The cathode 3 is composed of any suitable reconstructing material, such, for example, as mercury. A conducting member 6 projects through the cover of the container 1 and is sealed 60 thereinto and insulated therefrom by any suitable means, such as a joint 7. The inner end of the member 6 is provided with a tubular extension of conducting material provided with pins 9, preferably three in 65 number, adjacent to its lower end. A member 10 of refractory material, such, for example, as quartz or lava, is mounted on these pins by an ordinary bayonet joint, as is clearly shown in Figs. 6 and 7. A rod 11 of 70 refractory conducting material, such, for example, as tungsten, is inserted within the conducting extension 8 and is forged or cold rolled about a fin 12 of a material having a relatively low melting point, such, for example, as iron, copper or zinc. The lower end of the fin is some distance from the lower end of the rod 11 and rests upon the upper surface of the member 10, while the rod 11 extends into the neighborhood of the 75 cathode 3. A spring member 13 serves to keep the fin member 12 in close contact with the member 10 and also serves to conduct current to the refractory rod 11. Direct current is supplied to the member 6, and 80 thence to the rod 11, by a conductor 14. A refractory insulating shield 25 surrounds the members 6 and 8 and protects the same 85 from the main arc.

In the operation of my device, any suitable source of direct current is connected between the conductor 14 and the conductor 5, and maintains an arc between the lower end of the rod 11 and the cathode 3, maintaining the latter in an active condition. If a 90 source of alternating current be connected between the wires 4 and 5, positive waves will be allowed to pass, while negative waves will be stopped, as is well known in the art.

95 Since it is a difficult task to forge a refractory material, such as tungsten, about a fin as shown in Fig. 2, I may groove my tungsten as shown at 15—16 in Fig. 4, and crimp a metallic member 17 into the grooves. The member 17 may be of any suitable material having a relatively low melting point and will, by its engagement with the rod for a considerable length, provide ample holding power for all practical purposes. Fig. 5 illustrates still another form of elec- 100 105 110

trode wherein a refractory rod 20 is clamped to a rod 21 of relatively low melting point 21 by an ordinary band clamp 22.

I am aware that it is old in the arc lamp
5 art to mold carbon and compositions around
fins of low melting point and, accordingly,
I do not claim this idea broadly but have
restricted my claims to the modifications
10 necessary to apply this method of electrode
feeding to the vapor arc rectifier.

I claim as my invention:

1. In vapor electric apparatus, the combination
with an evacuated container, of a liquid
15 electrode therein, a consumable solid
electrode adjacent thereto, and means for
automatically compensating for the con-
sumption of said solid electrode.

2. In vapor electric apparatus, the combination
20 with an evacuated container, of a liquid
electrode therein, a solid electrode,
comprising a substantially vertical rod of
refractory conducting material, having its
25 lower end adjacent to the liquid electrode,
means for maintaining an arc between the
two electrodes, and means for automatically
feeding the refractory electrode downwardly
in accordance with the consumption thereof.

3. In vapor electric apparatus, the combination
30 with an evacuated container, of a liquid
electrode therein, a solid electrode,
comprising a substantially vertical rod of
refractory conducting material, having its
35 lower end adjacent to the liquid electrode,
and means for automatically maintaining an
arc of substantially constant length between
the two electrodes.

4. In vapor electric apparatus, the combination
40 with an evacuated metallic container
having an opening in the wall thereof, of a
conducting member passing through said
opening, an insulating gas-tight joint be-
tween said member and the wall of the con-

tainer, a liquid electrode within the container, and a consumable solid electrode adjacent thereto, said solid electrode being carried by said conducting member and being automatically adjustable with relation thereto in accordance with its rate of consumption.

5. In vapor electric apparatus, the combination
with an evacuated container having
an opening therein, of a conducting member
passing through said opening, a tubular ex-
tension on said conducting member within
the container, a refractory conducting rod
55 projecting from said tubular member, a feed
member of comparatively low melting point
within said tubular member and attached
to the refractory rod, and a refractory stop
member carried by the end of the tubular
60 member and acting as a rest for the end of
the feed member.

6. In vapor electric apparatus, the combination
with an evacuated container having
an opening therein, a conducting member
passing through said opening, a tubular ex-
tension on said conducting member within
the container, a refractory conducting rod
65 projecting from said tubular member, a feed
member of comparatively low melting point
70 within said tubular member and attached to
the refractory rod, of a refractory stop
member carried by the end of the tubular
member and acting as a rest for the end of
the feed member, and a refractory insu-
75 lating sleeve shielding said conducting mem-
ber and the tubular extension thereof.

In testimony whereof, I have hereunto
subscribed my name this 28th day of April,
1914.

DAVID C. DAVIS.
